US0D1076060S

(12) **United States Design Patent** (10) **Patent No.:** **US D1,076,060 S**
(45) **Date of Patent:** **** May 20, 2025**

(54) **AIRWAY DEVICE**

(71) Applicant: **ASHKAL DEVELOPMENTS LIMITED**, Douglas (IM)

(72) Inventors: **Muhammed Aslam Nasir**,
Bedfordshire (GB); **Ivan Crotaz**,
Berkshire (GB); **Andrew Honour**,
Buckinghamshire (GB)

(73) Assignee: **ASHKAL DEVELOPMENTS LIMITED**, Douglas (IM)

(**) Term: **15 Years**

(21) Appl. No.: **29/698,547**

(22) Filed: **Jul. 17, 2019**

(30) **Foreign Application Priority Data**

Jan. 18, 2019 (EM) 006067534
Jun. 12, 2019 (EM) 006575411

(51) **LOC (15) Cl.** **29-02**

(52) **U.S. Cl.**

USPC **D24/110.1**

(58) **Field of Classification Search**

(74) *Attorney, Agent, or Firm* — HAYES SOLOWAY P.C.

(57) **CLAIM**

The ornamental design for an airway device as shown and described.

DESCRIPTION

FIG. 1 is a top perspective view of an airway device incorporating our new design;

FIG. 2 is a bottom perspective view thereof;

FIG. 3 is bottom plan view thereof;

FIG. 4 is a top plan view thereof;

FIG. 5 is a left side view thereof;

FIG. 6 is a front elevation view thereof;

FIG. 7 is a rear elevation view thereof; and,

FIG. 8 is a right side view thereof.

1 Claim, 6 Drawing Sheets
